UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO.

MANIFOLDING SALES-BOOK.

1,295,264.

Specification of Letters Patent. Patented Feb. 25, 1919.

Application filed October 10, 1917. Serial No. 195,682.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to manifolding devices and with regard to its more specific features, to manifolding sales books.

An object of this invention is to provide a manifolding sales book by which three direct reading opaque paper copies of a record may be made and one reverse record.

A further object of the invention is to provide a device of the character described which will be simple and economical in construction and practical and efficient in manipulation.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming part of this specification, in which similar reference characters refer to similar parts throughout the several views,

(Figure 1 is a perspective view of a sales book embodying this invention; and

Fig. 2 is a side elevation showing the arrangement of the leaves.

In the drawings, the numeral 1 indicates a pad of record sheets, each sheet being folded upon itself twice to form a bound leaf 2 and an intermediate leaf 3 and an end leaf 4, and the sheet will preferably be folded upon itself in such a way that the end leaf will lie between the intermediate leaf and the bound leaf.

In order to transfer the record made upon the upper or intermediate leaf to the lower leaf of the top record sheet, a transfer sheet 5 will be provided which is preferably bound integrally with the pad 1, which sheet will be folded upon itself to form two superposed leaves as a bound leaf 6 and a free leaf 7, and the leaves 6 and 7 will be of such length

and so disposed that they may be interfolded with the leaves 2, 3 and 4 of the top record sheet successively, with the leaf 7 of the transfer sheet disposed between the free leaf 4 and the intermediate leaf 3 and with the bound leaf 6 of the transfer sheet disposed upon the bound leaf 2 of the record sheet.

In order to enable a quadruplicate record to be made, a second pad, as 9, may be provided and so disposed that its leaves may be inserted between the leaves of the top record sheet and between one of the leaves of the record sheet and a surface of the transfer sheet. As illustrated in the drawings, the pads 1 and 9 are attached respectively to supports 10 and 11, the opposite ends of which supports are hinged together as shown at 12, so that there is provided between the supports 10 and 11, a receptacle in which those leaves of the pad 9 upon which a record has been made may be placed, and in order to enable the book to lie flat, the support 11 will preferably be sufficiently longer than the support 10, to carry the stub portion of the pad 9 out from under the pad 1, as shown in the drawing.

In order to facilitate the removal of the upper end of the intermediate leaves 3 from beneath the transfer sheet, a notch 14 may be provided in the lower leaf of the transfer sheet and a notch, as 15, in the outer or free leaf of the transfer sheet and these notches will be so disposed as to expose a corner of the upper end of the intermediate leaf 3 when lying thereon.

In order, however, to facilitate the lifting of the outer or free end of the transfer leaf 7, the notch 14 will be deeper than the notch 15 or otherwise so disposed as to leave a portion of the transfer leaf 7 extending out over the notch 14 so as to be able to be readily grasped. In this wise a portion of the area of the notch of the transfer leaf 5 will be covered by the transfer leaf 7.

The manipulation of the book is as follows:

In order to place the book in the position illustrated in the figure, in which it is ready to have an inscription made thereon, the leaves of the pad 9 will be thrown back to expose the pad 1 and the upper edge of the intermediate leaf 3 of the upper record sheet is grasped at the point where it is exposed by the notches in the transfer sheet and drawn out from under the transfer sheet.

Thereupon the upper free leaf 7 of the transfer sheet will be lifted; one sheet from the pad 9 is then superposed upon the leaf 5 of the transfer sheet and the free leaf 4 of the record sheet is folded over the free leaf 7 of the transfer sheet. Thereupon the upper sheet of the pad 1 and the transfer sheet are folded together so as to bring the leaf 4 downwardly upon the sheet from the pad 9. The book is then in the position as shown in Fig. 1.

Any inscription which is then made upon the intermediate leaf will be transferred to the leaf 4 by the under face of the leaf 7 of the transfer sheet and will be transferred to the under face of the sheet from the pad 9 and to the upper face of the leaf 2 by means of the leaf 5 of the transfer sheet. The sheet comprising the leaves 2, 3 and 4 may then be drawn from the book and the sheet from the pad 9 may be inserted beneath the support 10, whereupon the manipulation may be repeated, as before described.

Thus by the above construction are accomplished, among others, the objects hereinbefore set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent, is:—

1. A manifolding sales book comprising, in combination, a plurality of sheets bound together along one edge to form a pad, each sheet being folded upon itself twice to form three superposed leaves, a transfer sheet bound integrally with said pad folded upon itself to form two superposed leaves, a pad of leaves connected to said first mentioned pad in position to have its leaves interposed between the leaves of the transfer sheet, said transfer leaves being provided with cut-outs whereby portions of the unbound leaves of the top sheet of said first mentioned pad are exposed from beneath both leaves of the transfer sheet.

2. A manifolding sales book comprising, in combination, a plurality of sheets bound

together along one edge to form a pad, each sheet being folded upon itself twice to form three superposed leaves, a transfer sheet bound integrally with said pad folded upon itself to form two superposed leaves, a pad of leaves connected to said first mentioned pad in position to have its leaves interposed between the leaves of the transfer sheet, said transfer leaves being provided with cut-outs whereby portions of the unbound leaves of the top sheet of said first-mentioned pad are exposed from beneath the transfer sheet, the bound leaf of the transfer sheet being cut away more at one point than the free leaf of the transfer sheet whereby the free leaf of the transfer sheet may be readily grasped without grasping the bound leaf.

3. A manifolding sales book comprising, in combination, a plurality of sheets bound together along one edge to form a pad, each of said sheets being folded upon itself to form three superposed leaves, a transfer sheet bound integrally with said pad and folded upon itself to form two superposed leaves adapted to be inserted between the leaves of the top sheet of said pad, a support hinged to said pad at the end thereof opposite the binding, extending out from under the pad at the bound edge of the pad, and a pad of leaves attached to the extended portion of said support in position to be inserted between the leaves of the top sheet of the first mentioned pad.

4. A manifolding sales book comprising, in combination, a pad of superposed record leaves, and a folded transfer sheet adapted to lie thereon, each leaf of said sheet being shaped to expose a portion of the uppermost record leaf, when lying in folded condition thereon.

5. A manifolding sales book comprising, in combination, a pad of superposed record leaves, and a folded transfer sheet adapted to lie thereon, each leaf of said sheet being notched to expose a portion of the uppermost record leaf, when lying in folded condition thereon.

6. A manifolding sales book comprising, in combination, a pad of superposed record leaves, and a folded transfer sheet adapted to lie thereon, each leaf of said sheet being notched to expose a portion of the uppermost record leaf, when lying in folded condition thereon, the uppermost leaf of said transfer sheet covering a portion of the area of the notch in the lower transfer leaf.

In testimony whereof I affix my signature, in the presence of two witnesses.

EDWARD KIRBY BOTTLE.
